EXHAUST MECHANISM FOR INTERNAL-
COMBUSTION ENGINES

Egbert Clark, Gamboa, C. Z.

Application March 15, 1944, Serial No. 526,603

1 Claim. (Cl. 123—75)

1

This invention relates to internal combustion engines and it aims to provide a novel exhaust means or mechanism which will result in the production of more power to the engine, without additional fuel, and hence, result in greater economy.

It is particularly aimed to provide such a means as will be applicable to either two- or four-cycle engines and which will include high pressure exhaust through the exhaust manifold as usual, and low pressure exhaust to the atmosphere, both the high pressure and low pressure exhausts occurring during the common exhaust stroke of the piston.

The more specific objects and advantages will become apparent from a consideration of the description following taken in connection with accompanying drawings illustrating an operative embodiment.

In said drawings:

Figure 1 is a view in central longitudinal section through the cylinder and associated parts of a two-cycle internal combustion engine, the piston being in position for firing;

Figure 2 is a view similar to Figure 1 with the piston shown at the end of an exhaust stroke;

Figure 3 is a cross section taken on the line 3—3 of Figure 2; and

Figure 4 is a view similar to Figure 1 but through a four-cycle internal combustion engine.

Referring specifically to the drawings wherein like reference characters designate like or similar parts, and first to the two-cycle internal combustion engine shown in Figures 1 to 3, 10 designates a cylinder in which a conventional piston 11 is adapted for reciprocation. The intake pipe is shown at 12, the spark plug at 13 and the usual exhaust pipe leading from said cylinder is disclosed at 18. In this instance, a high-pressure exhaust pipe 14 leads from cylinder 10 to the atmosphere and contains a check-valve at 15, which is a non-return valve as it is inclined so that it can only open outwardly under high pressure and cannot open inwardly. This valve may be of any suitable design for example, may be pivoted at 16 to a screw or other removable plug 17.

It will be noted that when the exhaust stroke of the piston 11, that is, in moving from the position of Figure 1 to the position of Figure 2, that the pipe 14 is first uncovered and the pipe 18 then uncovered, during the same or common stroke of such piston.

In the operation of the engine, as the piston 11 moves downwardly on its exhaust stroke, it

2

first uncovers the pipe 14 which because of the high pressure, would force some of the gas out of the same undiluted. In continuance of such travel, the piston also uncovers the low-pressure pipe 18, allowing the cylinder to thus be thoroughly scavenged and filled with fresh air for the next cycle. Since the gas in the high pressure manifold would be free from dilution, it would have a higher temperature than normal two-cycle engines. The gas obtained may be applied to any useful purpose.

Present-day two-cycle internal combustion engines of industrial and marine type use some kind of waste heat boilers for the conversion of waste heat for several uses which has its limitation owing to the mixing of the cool air with the hot exhaust gas, and also the back pressure imposed on such engines which tends to reduce fresh air to the cylinder and a reduction in power delivered from the engine. My invention overcomes these disadvantages.

The beneficial results attained with the two-cycle engine structure of Figures 1 to 3 may also be obtained in a four-cycle engine as disclosed in Figure 4. This engine has a cylinder 18 in which a piston 19 is reciprocable. The intake pipe is shown at 20 in connection with an intake valve 21. The spark plug is shown at 22. The usual exhaust pipe 26 communicates with the cylinder 18 and is closed or controlled by an exhaust valve 24. The pipe 23 includes a plug 17' to which a non-return valve 15' is pivoted at 16' so as to function in the same manner as valve 15. Pipe 23 serves as a high pressure exhaust pipe and it communicates at a port 25 through valve 24 with the cylinder, which may be formed integral therewith and which communicates with the atmosphere, being under control of a mechanically operated valve 27. Such valve may be either directly operated from the engine or externally timed and operated electrically, hydraulically, etc., of poppet, gate, sleeve, or other type. The valve is adapted to be mechanically and positively operated from any suitable moving part of the engine.

In the operation of this four-cycle engine of Figure 4, valve 24 is opened mechanically by operation of the engine, allowing the hot gases to pass the exhaust valve 24, and valve 15'. At a given point of piston travel on the exhaust stroke in which maximum power may be obtained from the exhaust, mechanically operated valve 27 which is normally closed, would open, allowing the remainder of the gases to flow to the atmosphere, thus establishing communication between

the cylinder 18 and the atmosphere. The gas passing the valve 15 could be used or applied to any desired work such as the operation of a gas turbine, to a piston type engine, to providing additional power to the shaft of the engine, or be used to run any auxiliary mechanism such as the super-charger, water pump, compressor or the like.

With the present invention, more power may be obtained from a given internal combustion engine without the use of extra fuel and hence greater economy per unit; also the exhaust gas from the engine may be used to produce steam in boilers for heat during winter, in laundries or the like for heating water, etc., therefore reducing the expense of the plant; in the invention the gas trapped in the high-pressure manifold may be used to run exhaust gas turbines which in turn will drive super-chargers for super-charging the engine, to run water pumps, run generators for lights, ventilators for engine room extra power to the shaft of the engine all without the use of extra fuel. The gas may also be used without any engine capable of converting heat, pressure or both into power (reciprocating, boilers, etc.). It may also be used to clean exhaust gas or carbon which might increase the wear of engines and the gas could be passed, first, through a usual spark arrester, which by centrifugal action would clean the gases of impurities. There would be no back pressure on the engine which would tend to reduce the output as the final stage of the cycle would be reduced to atmospheric pressure through low-pressure manifold. It is possible to use the invention with the Buchi turbo-charge system connected to either high or low pressure manifolds. The auxiliaries used (turbine-reciprocating) may be integral with the engine or separate therefrom, geared, with or without clutches, as the design will allow for the most efficient operation. An airplane engine at low altitude could use part of the exhaust gas to run generators, etc., but at high altitudes all could be diverted for use of the super-charger.

The invention will prevent the mixture of cold, scavenging air with the hot exhaust gas such as

two-cycle and super-charged engines. The invention is applicable to two- or four-cycle internal combustion engines, double or single acting, auto or Diesel cycle and adaptable to new as well as old engines.

It is known that the thermal efficiencies and heat-distribution efficiency of internal combustion engines are (Diesel) powered to shaft 30 percent, friction 9 percent, cooling water 25 percent, exhaust gases 28 percent, radiation and other losses 8 percent. After using 30 percent for power, the largest single loss is through the exhaust. This invention tends to reduce this loss. The principal parts of the invention are the extra exhaust manifold as a duplicate of the usual exhaust manifold, directly connected from each cylinder and known as the high-pressure manifold; a non-return valve, one for each cylinder at the opening of high-pressure manifold and automatically operated to trap exhaust gas in the high-pressure manifold for further use; and the mechanically operated valve, one for each cylinder, situated at the opening of the low-pressure manifold.

It will be understood that the structure of my invention may be embodied in existing engines by way of attachment, as well as being capable of manufacture at the factory into such engines.

Various changes may be resorted to provide they fall within the spirit and scope of the appended claim.

I claim as my invention:

In an internal combustion engine, in combination with a cylinder and a piston reciprocable therein, a high pressure exhaust pipe leading from the cylinder under control of an exhaust valve, a low pressure exhaust pipe close to and in communication with the high pressure exhaust pipe at the end thereof controlled by said exhaust valve, arranged to communicate with the atmosphere, valve means operable to open the low pressure exhaust pipe subsequent to opening of the exhaust valve, the first-mentioned exhaust pipe having a check-valve therein constrained to open outwardly.

EGBERT CLARK.
